BOBBIN ROTATION RESTRAINING MEANS
FOR SEWING MACHINESHerman Ritter, Cranford, N. J., assignor to The
Singer Manufacturing Company, Elizabeth,
N. J., a corporation of New Jersey

Application January 29, 1949, Serial No. 73,638

5 Claims. (Cl. 112—181)

1

This invention relates to horizontal axis rotary hook stitch-forming mechanisms for sewing machines of the lock stitch type and it has as its primary object to provide an improved and simplified means to apply to the bobbin of lower thread sufficient restraint to prevent overrunning of the bobbin and spilling of thread therefrom.

Another object of the invention is to provide, in a device of this nature, readily adjustable means for varying the rotation restraining force applied to the bobbin.

As used herein, the term "bobbin" is intended to mean any wound mass of thread, as used in lock stitch sewing machines, whether or not the thread is wound upon a spool having a central hub and side flanges as shown in the drawings. In other words, the invention is equally adaptable to stitch forming mechanisms which use a so-called "cop" of thread, the wound cop being the equivalent of the wound bobbin shown in the drawings.

Drawings depicting a preferred form of the invention are annexed as a part of this disclosure and in such drawings Fig. 1 is a vertical sectional view showing certain stitch forming elements of a lock stitch sewing machine embodying the present invention.

Fig. 2 is an outer face view of a thread-case comprising one of the elements of the stitch forming mechanism.

Fig. 3 is an inner face view of the thread-case showing my improved bobbin rotation restraining device therein.

Fig. 4 is an enlarged horizontal section taken on the lines 4—4 of Figs. 1 and 3.

Fig. 5 is an enlarged vertical section taken substantially on the line 5—5 of Fig. 3, together with a portion of the thread-case carrier.

Fig. 6 is a detail perspective view of the improved bobbin rotation restraining element.

Referring more specifically to the drawings, the invention is disclosed as embodied in a sewing machine stitch forming mechanism of the lock stitch type, comprising a rotary hook 1 secured upon a horizontal drive shaft 2 and formed with an inner annular raceway 3 adapted to receive the peripheral flange 4 of a thread-case carrier 5. This carrier has a cavity 6, a back wall in the form of a conventional diameter bar 7 and a central thread-case supporting stud 8 carried by the diameter bar. Secured to and cooperating with the carrier 5, to house a bobbin B, is a cup-like thread-case 9 having a front wall 10, a central sleeve 11 adapted to fit upon the stud 8, and

5 a skirt-portion 12 fitted within the cavity 6 in the thread-case carrier. Conventional latch means, designated generally as L, is carried by the thread-case and engages the outer end portion 13 of the pin 8 to releasably lock the thread-case 9 to its carrier 5. The bobbin may comprise a central hub 13 (journaled upon the sleeve 11) upon which the thread T is wound, and side flanges 14. The rotary hook 1 takes loops of needle thread t from a reciprocating eye-pointed needle n and passes those loops about the bobbin B, thereby forming conventional lock stitches as is well understood.

15 The improved bobbin rotation restraining device preferably comprises a thin spring steel member S of substantially J-shape, having a shank portion 15, and a curved foot portion 16. The shank portion is secured flatwise upon the inner face of the front wall 10 of the thread-case 9 by a screw 17 passing through an aperture 18 in the upper end of the shank and threaded into a tapped hole 19 in the wall 10. As shown most clearly in Figs. 1 and 4, the foot portion 16 20 of the member S is bent laterally out of the plane 25 of the shank portion 15 and bears against the adjacent side flange 14 of the bobbin B, thereby forcing the rear flange of the bobbin against the back wall of the thread-case carrier. Pressure 30 of the foot portion 16 against the bobbin flange creates friction which retards rotation of the bobbin and thus preventing overrunning of the bobbin and the consequent spilling of thread.

35 The amount of friction applied to the bobbin may be regulated by means of an adjusting screw 20 threaded in a tapped hole 21 in the front wall 10 of the thread-case 9. As shown most clearly in Figs. 3 and 5, the inner end of the screw 20 bears upon the outer face of the shank portion 15 of the rotation restraining device S adjacent 40 its lower end.

45 Referring to Fig. 5 it will be seen that inward adjustment of the screw 20 causes an increase in the pressure applied to the bobbin by the foot portion of the spring member S and thereby further restricts rotation of the bobbin. Outward adjustment of the screw has the opposite effect. To prevent accidental shifting of the screw 20, by vibration of the machine, the inner end of the screw is preferably split, as indicated at 20^a, 50 and is slightly spread so that when it is threaded into the hole 21 it presses outwardly against the threads in the hole and is thereby frictionally held against rotation. Thus the tension of the 55 spring and the pressure applied to the bobbin may

be adjusted to a nicety and maintained constant throughout the operation of the machine.

It will be apparent that by forming the spring member S of J-shape with the straight shank 15 and the arcuate foot portion 16, the member may be of considerable length, giving maximum flexibility; that it may be secured in a conventional thread-case without taking up any substantial amount of room; and that it applies the restraining force to the outer marginal portion of the bobbin flange where it is most effective.

Having thus set forth the nature of the invention, what I claim herein is:

1. A stitch forming mechanism for a sewing machine including a hook member rotatable on a horizontal axis, a thread-case carrier journaled in said hook member, a cup-shaped thread-case in said thread-case carrier and having a front wall and a cylindrical skirt portion forming a bobbin-receiving cavity in which a bobbin is rotatably mounted; and a bobbin rotation restraining device mounted in said thread-case and comprising a flat spring member having a shank portion secured flatwise to the inner face of said front wall and an offset foot portion located out of the plane of said shank portion and arranged to press against the bobbin in said cavity.

2. A stitch forming mechanism for a sewing machine including a rotatable hook member, a thread-case carrier journaled in said hook member, a cup-shaped thread-case in said thread-case carrier and having a vertical front wall and a skirt portion forming a bobbin-receiving cavity in which a bobbin is rotatably mounted; a bobbin rotation restraining device mounted in said thread-case and comprising a spring metal member having a shank portion secured flatwise to the inner face of said front wall and an offset foot portion located inwardly of the plane of said shank portion and arranged to press against a bobbin in said cavity; and manually adjustable means carried by the front wall of said thread-case to vary the location of said foot portion relative to said front wall to vary the amount of pressure applied by said foot portion to said bobbin.

3. A stitch forming mechanism for a sewing machine including a rotatable hook member, a thread-case carrier, a cup-shaped thread-case in said thread-case carrier and having a front wall and a skirt portion forming a bobbin-receiving cavity in which a bobbin is rotatably mounted; a bobbin rotation restraining device mounted in said thread-case and comprising a spring metal member having a shank portion secured flatwise to the inner face of said front wall and an offset foot portion located inwardly of the plane of said shank portion and arranged to press against

a bobbin in said cavity; and an adjusting screw threaded through said front wall and bearing against said bobbin rotation restraining device to vary the offset position of said foot portion and thereby vary the amount of pressure applied by said foot portion to said bobbin.

4. A stitch forming mechanism for a sewing machine including a rotary hook, a thread-case carrier journaled in said hook and having an open-face cavity and a rear wall; a cup-shaped bobbin-holding thread-case fitted within said cavity and having a front wall; and a bobbin rotation restraining device located within said thread-case and comprising a substantially J-shaped spring metal member having a shank portion fixedly secured to the inner face of the front wall of said thread-case and a foot portion deflected inwardly out of the plane of said shank portion and adapted to bear upon a bobbin in said thread-case and to force the bobbin into frictional contact with the rear wall of said thread-case carrier.

5. A stitch forming mechanism for a sewing machine including a rotary hook, a thread-case carrier journaled in said hook and having an open-face cavity and a rear wall; a cup-shaped bobbin-holding thread-case fitted within said cavity and having a front wall and a skirt portion affording a bobbin-receiving cavity in which a bobbin is rotatably mounted; a bobbin rotation restraining device located within said thread-case and comprising a substantially J-shaped spring metal member having a shank portion secured flatwise to the inner face of the front wall of said thread-case and an offset foot portion located inwardly of the plane of said shank portion and arranged to press against a bobbin in said bobbin-receiving cavity to force the bobbin into frictional contact with said rear wall of the thread-case carrier; and an adjusting screw threaded through the front wall of said thread-case and bearing against said bobbin rotation restraining device to vary the amount of pressure applied by said foot portion to said bobbin.
